DESIGN FOR A GAME BOARD

Benjamin F. Hirsch, Chicago, and Stanley A. Chmielewski, Cicero, Ill.

Application March 23, 1945, Serial No. 118,651

Term of patent 14 years

(Cl. D34—5)

To all whom it may concern:

Be it known that we, Benjamin F. Hirsch and Stanley A. Chmielewski, citizens of the United States, residing respectively at 702 Buckingham Place, Chicago, and 2919 South 49th Avenue, Cicero, in the county of Cook and State of Illinois, have invented a new, original, and ornamental Design for a Game Board, of which the following is a specification, reference being had to the accompanying drawing, forming part thereof.

Fig. 1 is a plan view of a game board embodying our design; and

Fig. 2 is a side elevation of same.

The drawing is lined to indicate contrasting colors.

We claim:

The ornamental design for a game board, as shown and described.

BENJAMIN F. HIRSCH.
STANLEY A. CHMIELEWSKI.
